United States Patent Office.

CHARLES F. HAGER, OF BUFFALO, NEW YORK.

Design No. 3,734, dated November 2, 1869.

DESIGN FOR A RACK-PULLEY.

The Schedule referred to in these Letters Patent and making part of the same.

To all whom it may concern:

Be it known that I, CHARLES F. HAGER, of Buffalo, in the county of Erie, and State of New York, have invented a new and useful Design for Rack-Pulleys; and I do hereby declare the following to be a clear and exact description of the nature thereof, sufficient to enable others skilled in the art to which my invention appertains to fully understand and use the same, reference being had to the accompanying drawings, which fully illustrate my said invention, and in which—

A is the bracket, to which is connected the cylindrical tube B.

The pulley-holder C is partly angular, and is continued into a crook, for supporting the pulley.

The lower portion of the pulley-holder is screw-threaded, and surrounded by a spiral spring, and receives a winged nut, b.

Having thus described my invention, What I claim as new, and desire to secure by Letters Patent, is—

The design for rack-pulleys, substantially as herein represented and described.

In witness whereof, I have hereunto signed my name, in the presence of two subscribing witnesses.

CHAS. F. HAGER.

Witnesses:

J. R. DRAKE,
C. N. WOODWARD.
